UNITED STATES PATENT OFFICE.

EDWIN J. MURPHY, OF SCHENECTADY, NEW YORK, ASSIGNOR TO GENERAL ELECTRIC COMPANY, A CORPORATION OF NEW YORK.

ELECTROMAGNETIC SWITCH.

1,231,412.

Specification of Letters Patent. Patented June 26, 1917.

Application filed July 13, 1914. Serial No. 850,598.

To all whom it may concern:

Be it known that I, EDWIN J. MURPHY, a citizen of the United States, residing at Schenectady, in the county of Schenectady, 5 State of New York, have invented certain new and useful Improvements in Electromagnetic Switches, of which the following is a specification.

This invention relates to electromagnetic 10 switches and has for its object the provision of a device of this character in which the contacts cannot stick or freeze together under the most trying conditions of service and at the same time are spring pressed 15 apart at all times.

In the operation of electromagnetic switches, especially as used in the control of electric motors where the switches are operated very frequently and the currents are 20 heavy, it sometimes happens that the arc formed between the contacts fuses the metal and causes the contacts to stick together, due to the formation of a slight weld between them. This most frequently happens when 25 the magnetizing winding is not energized long enough to cause the contacts to be brought firmly into engagement with each other in their final position, but is only energized for an instant so that the contacts 30 just touch and then separate. This also happens sometimes because of the slow opening of the contacts due to slow decrease of magnetic pull and other causes. In the type of contact for electromagnetic switches now 35 well known, in which the contacts slide or roll upon each other to produce a wiping action, any slight welding or sticking will be overcome by the wiping action if the contacts are closed or "wiped home." If, 40 however, the contacts merely engage or "kiss" without being wiped to the final position, a weld might form which would hold the contacts in the closed position against the tendency of gravity or the 45 spring to open the switch. One of the objects of my invention is to overcome this difficulty and make it practically impossible for the contacts of the switch to stick together in the manner above described.

50 Another object of my invention is to provide a switch which is spring pressed to the open position as distinguished from being biased to the open position by gravity. It is frequently desirable that the contactor 55 should be capable of being tilted at an angle say of 45° or more without danger of the

contacts dropping closed. On shipboard, for instance, a contactor must be arranged so that the contacts cannot possibly drop closed under the worst conditions of rolling and 60 pitching. One of the inherent difficulties in making a switch of this kind with spring opened contacts is that if the spring is strong enough to be of any advantage in causing a strong pressure between the contacts in closed position, it will be so strong 65 that the magnet cannot move it from the open position. As the contactor approaches closed position, the closing force increases very rapidly, but in the open position the 70 force is relatively weak and it is therefore necessary that the spring should be weak in the open position.

In carrying out my invention, I provide a switch which is spring pressed to the open 75 position, the contacts being forced apart near the closed position with sufficient force to break any weld which might possibly form. The arrangement is such that the effective pressure tending to hold the contacts apart is less when the switch is in the open position than it is just before the switch closes. This is accomplished by decreasing 80 the leverage at which the magnet acts upon the spring just prior to the engagement of 85 the contacts so that the effective pressure tending to hold the contacts open will be considerably increased. From this point on until the contacts reach their final position, there is a strong spring pressure between the 90 contacts so that any weld which might form between the contacts will be instantly broken, and while it might be possible that the contacts would be brought into engagement with each other in such a way as to 95 form a weld, this weld would be immediately broken by the strong spring pressure which acts over a sufficient range to break any weld which could form. Other objects and purposes of my invention will appear in the 100 course of the following specification in which I have shown my invention embodied in concrete form for purposes of illustration.

In the accompanying drawing, Figure 1 represents a side view of an electromagnetic 105 switch embodying my invention; Fig. 2 is a front view of the same; Figs. 3, 4 and 5 are diagrammatic views showing the parts in different positions; and Fig. 6 is a central section through the switch arm.

Referring first to Figs. 3, 4 and 5, it will 110 be seen that the magnet frame is of the usual

carrying member 17 and presses the latter against the stop 19. This spring engages 15 the member 17 between the pivot and the stop, and the point of engagement is important because it affects the leverage at which the spring is compressed. The armature member is provided with a shoulder 21 20 which acts as a stop for the member 17 when the latter has turned on its pivot through a small angle.

In Fig. 3 the switch is shown in the open position. When the armature member 25 13 starts to move toward closed position the pivot pin 18 on the armature of course moves with the armature, but the spring 20 forces the lower end of the member 17 against the stop 19. The effective action of 30 the spring 20 tending to move the contacts apart is therefore due to a compound leverage. Representing the distance between the pivot pin 18 and the stop 19 by a , and the distance between the spring and the stop 19 35 by b , and the distance between the pivot pin 14 and the pivot pin 18 by c , then the effective action of the spring tending to hold the contacts apart is due to the force of the 40 spring acting at the distance $C \times \frac{b}{a}$. The nearer the spring is located to the stop 19 the less will be the effective leverage at which the spring acts and hence the less effective force there will be to hold the armature in the open position. When the armature moves inward, the member 17 slides and rolls on the stop 19 and a relatively 45 large movement of the member 13 compresses the spring a relatively small amount.

50 This will be seen by reference to Fig. 4. In this figure the switch has reached the position in which the effective pressure of the spring tending to open the contacts is increased. This is brought about by the engagement of the lower end of the member 55 17 with the shoulder 21. From this point on in the movement of the switch arm it will be seen that the spring will act directly upon the armature member since the member 17 60 now moves as a unit with the member 13. Relatively small movement of the armature to closed position now compresses the spring a relatively large amount. When the contacts 15 and 16 engage, they wipe or 65 roll on each other and the member 17 is

would tend to cause the contacts to stick together will be overcome by the spring tension acting through the distance shown between the contacts in Fig. 4. In the final position (Fig. 5) the contacts have "wiped" on each other and in so doing have compressed the spring still farther. 80

In the actual construction shown in Fig. 85 1, two springs 20 are used, one on each side of the armature member. These springs are made adjustable by slidable members 22 which are held in various positions by screw 23 which slides in the slot 23'. The contact carrying member is made in the form of a yoke 24 so that one of the springs acts against each leg of the yoke. A bar 25 secured to the armature member corresponds with the shoulder 21—Figs. 3 to 5—95 and projects beyond the armature member at each end so as to be engaged by the legs of the contact carrying member. A plate 26 is secured in a stationary position by means of a rod 27 which is secured in the frame of the magnet and passes through a clearance hole in the armature member. Nuts 28 on this rod secure the plate in place. 100

Screws 19 form stops corresponding to the stop 19 in Fig. 3. The operation and general arrangement of parts is identical with that already described in connection with Figs. 3 and 5 and no further description is therefore deemed necessary. 105

It will be seen that the electromagnetic 110 switch above described is spring pressed to the open position but the force necessary to move the switch from the open position to the intermediate position shown in Fig. 4 is relatively small as compared with the force 115 necessary to move it the remainder of the distance. This makes a very strong pressure between the contacts for a short distance, enough to break any weld which might form, and produce a good spring 120 pressure on the movable contact in the closed position. On the other hand, in the open position, the spring is weak enough so that it can be readily moved over the wide air gap which then exists. While I have described my invention as embodied in concrete form and as operating in a specific manner in accordance with the provisions of the patent statutes, it should be understood 125 that I do not limit my invention thereto, 130

since various modifications thereof will suggest themselves to those skilled in the art without departing from the spirit of my invention, the scope of which is set forth in the annexed claims.

What I claim as new and desire to secure by Letters Patent of the United States, is:—

1. An electromagnetic switch comprising a magnetizing winding, a fixed contact, a pivoted armature member having a contact mounted thereon and spring pressed away from the fixed contact so as to have a resilient movement with reference to the armature member, and means whereby the leverage at which the spring acts upon the armature member tending to keep the contacts apart is decreased before the movable contact reaches its closed position.
2. An electromagnetic switch comprising a magnetizing winding, a fixed contact, an armature member, a contact having a resilient mounting thereon to permit a yielding movement with reference to the armature member and press the armature member toward open position, and means whereby the effective pressure tending to hold the contacts apart is increased when the armature member reaches a predetermined position in the closing movement.
3. An electromagnetic switch comprising a magnetizing winding, a fixed contact, an armature member having a contact movably mounted thereon, and spring pressed away from the fixed contact, and means whereby the spring pressure tending to hold the contacts open is substantially uniform during the closing movement until the armature member reaches a predetermined position and is then increased.
4. An electromagnetic switch comprising a magnetizing winding, a fixed contact, an armature member having a contact pivoted thereon to coöperate with the fixed contact, a spring interposed between the pivoted contact and a stationary part of the switch so that the contacts will be held apart thereby and engage with a yielding pressure, and means whereby the effective pressure tending to hold the contacts apart is increased when the armature member reaches a predetermined position in the closing movement.
5. An electromagnetic switch comprising a magnetizing winding, a fixed contact, an armature member, a contact pivoted on said armature member to coöperate with said fixed contact, a spring interposed between a stationary portion of the switch and said pivoted contact tending to turn the latter on its pivot toward the fixed contact, a fixed stop against which the contact is pressed by the spring, and a stop on the armature member which engages the pivoted contact at a predetermined position in the closing move-

ment so that further movement of the armature member moves the pivoted contact away from the fixed stop.

6. An electromagnetic switch comprising a magnetizing winding, a fixed contact, an armature, a contact carrying member pivoted thereto, a fixed stop in the path of said contact member to prevent it from rotating in a direction to cause engagement of the contacts, a spring mounted to press the member against the stop and bias the armature to open position, and a stop on the armature which engages the pivoted contact member at a predetermined position in the closing movement so that further movement of the armature moves the contact member away from the fixed stop.

7. An electromagnetic switch comprising a magnetizing winding, a fixed contact, an armature, a contact carrying member pivoted thereto, a stop on the armature which limits the rotation of the contact member on its pivot in a direction to engage the fixed contact, a spring engaging said member between the pivot and the stop and tending to force it against the latter, and a fixed stop between the spring and the stop on the armature which acts as a fulcrum for the contact carrying member in compressing the spring during the closing movement until the contact carrying member engages the stop on the armature and is moved away from the fixed stop.

8. An electromagnetic switch comprising a magnetizing winding, a fixed contact, an armature member having a contact pivotally mounted thereon, and spring pressed away from the fixed contact so that there will be a yielding pressure between the contacts when they engage, and means whereby the spring pressure tending to hold the contacts open is substantially uniform during the closing movement until the armature member reaches a predetermined position and is then increased.

9. An electromagnetic switch comprising a magnetizing winding, a fixed contact, an armature member, a contact having a resilient mounting which permits yielding movement with reference to the armature member and forces the contact away from the fixed contact, and means whereby the pressure tending to hold the contacts apart is substantially uniform during the closing movement until the armature member reaches a predetermined position and is then increased.

In witness whereof, I have hereunto set my hand this 11th day of July, 1914.

EDWIN J. MURPHY.
